UNITED STATES PATENT OFFICE.

JOHN S. SIMMONS, OF NEW YORK, N. Y.

GAS-REGULATOR FOR SELF-GENERATING STEAM-RADIATORS.

1,112,852.

Specification of Letters Patent.

Patented Oct. 6, 1914.

Application filed November 8, 1913. Serial No. 799,875.

To all whom it may concern:

Be it known that I, JOHN S. SIMMONS, a citizen of the United States, residing in the borough of Brooklyn, county of Kings, city and State of New York, have invented a new and useful Improvement in Gas-Regulators for Self-Generating Steam-Radiators, of which the following is a specification.

- 10 My invention relates to the class of steam radiators, of which one species is shown in the application for patent of George W. Noble, filed February 21, 1913, Serial No. 749,875, in which a gas burner is arranged 15 to heat a water containing member of the radiator serving as a boiler, so as to generate steam therein, and the flow of gas through the supply pipe is automatically regulated by the steam pressure acting on a spring- 20 pressed pressure diaphragm, which controls the gas supply valve, so that no more gas will be consumed than is necessary to maintain the desired pressure in and heat from the radiator.
- 25 My present invention consists of novel means for adjusting the tension of the spring acting on the valve-carrying diaphragm, to suit different gas pressures and also the desired steam pressure, as herein- 30 after set forth.

In order that my invention may be fully understood I shall first describe in detail the mode in which I have carried the invention into practice and then particularly 35 point out the invention in the claims.

Reference is to be had to the accompanying drawings forming part of this specification in which like parts are designated by the same numbers throughout.

40 Figure 1 is a sectional view showing the gas regulating valve in which I have reduced my invention to practice. Fig. 2 is a cross-sectional view of the same on the line 2—2, Fig. 1.

45 In the drawings, 1 is the lower steam generating member or boiler of the radiator; 2 is the chamber containing the diaphragm carrying the gas regulating valve 3; 4 is the pipe connecting the boiler with the steam side of the chamber 2; 5 is the gas inlet pipe

leading into the gas side of the chamber 2; 6 is the gas outlet pipe leading outward therefrom through a tube 7 protruding from the wall of the gas chamber toward the valve 3, the open end of which tube 7 forms 55 the valve seat; 8 is the spring coiled around the protruding tube 7 and pressing against the diaphragmatic valve 3 against the steam pressure on the other side thereof; and 9 is the gas burner fed by the gas outlet pipe 6 60 to heat the boiler 1. In the present case the protruding gas tube 7 is fixed to the chamber wall.

To adjust the valve 3 to different gas pressures and the desired steam pressure, I provide means for adjusting the pressure of the spring 8 against the valve diaphragm, preferably, by providing in the gas chamber a spring compressing member 10, here consisting of a collar 11 surrounding the gas 70 tube 7 bearing against the outer end of the spring 8, and working in a recess 12 surrounding the base of the tube 7, the collar having diametrically opposite arms 13 and 14, working in corresponding recesses on 75 opposite sides of the recess 12.

Against the arm 13 of the spring compressing member 10 bears the inner end of an adjusting screw 15, projecting through and threaded in the wall of the chamber, so 80 that by turning the screw 15 from the outside, the spring compressing member 10 can be swung on the end of its arm 14 acting as a pivot, to compress the spring 8 more or less axially and thus vary the resistance of 85 the valve diaphragm to the steam pressure more or less as desired. I also provide for adjusting the by-pass 16, which in this case leads from the gas inlet to the gas outlet around the valve 3, by forming in the by- 90 pass a valve seat 17, which is adapted to be closed by the end of an axially adjustable screw 18 acting as a valve and projecting through and threaded in the wall of the by-pass, so that by turning the screw 18 95 the by-pass can be opened more or less to suit the gas pressure.

I claim as my invention:

The combination, with the chamber having two heads, the valve diaphragm there- 100

22
between, the pressure pipe leading through one head, and the gas tube projecting from the other head toward the valve diaphragm, of an axially movable collar embracing the
5 gas tube, a spring coiled on said gas tube between the valve diaphragm and the collar, a lever arm for moving said collar and

compressing the spring axially, and an adjusting screw acting on said lever arm.

JOHN S. SIMMONS.

In presence of—
PHILLIP WIEGAND,
CLARENCE L. BURGER.
